UNITED STATES PATENT OFFICE.

VICTOR E. WASSERLEIN, OF NEW YORK, N. Y., ASSIGNOR TO WASSERLEIN, FROES COMPANY, INC., A CORPORATION OF NEW YORK.

CARBURETER FUEL CONTROL.

1,392,724.

Specification of Letters Patent.

Patented Oct. 4, 1921.

Application filed April 9, 1917. Serial No. 160,776.

To all whom it may concern:

Be it known that I, VICTOR E. WASSERLEIN, a citizen of the United States, and resident of New York, in the county of New York 5 and State of New York, have invented certain new and useful Improvements in Carbureter Fuel Controls, of which the following is a specification.

This invention relates to improvements in 10 the atomizer type of carbureters and relates more especially to fuel control means therefor.

The object of the invention is to provide 15 air and fuel control means for a carbureter whereby richness of the mixture fed to the intake manifold of the engine may be varied and means for protecting the carbureter against backfire from the engine provided.

Another object is to provide a novel form 20 of charge receiving and mixing chamber whereby proper proportions of air will be admitted to regulate the richness of the combustible charge under varying conditions.

Another object is to provide a compensating 25 valve for preventing backfire to the carbureter.

With these and other objects in view, the invention consists in certain novel features of construction as hereinafter shown and described, and then specifically pointed out in 30 the claims, and in the drawings illustrative of the preferred embodiment of the invention.

In the accompanying drawing:

35 Figure 1 represents a vertical section through the carbureter with the valves in neutral or normal position.

Fig. 2 is a fragmentary vertical section 40 through the combined fuel and air valve and charge forming chamber with the valves shown closed ready for priming.

Fig. 3 is a similar view taken at right angles to Figs. 1 and 2 showing the air valve and the nozzle in full open position, the 45 valve and nozzle being shown in side elevation.

Fig. 4 is a detail perspective view of the combined air valve and charge forming chamber.

50 Fig. 5 is a detail perspective view of the compensating valve constituting a part of this invention.

Fig. 6 is a fragmentary vertical section

showing a slightly different form of the combined air valve and charge forming 55 chamber and the fuel supply nozzle, and,

Fig. 7 is a horizontal section taken through Fig. 1.

In the embodiment illustrated a carbureter casing 1 is shown having a reduced outlet 2 merging into a conduit 1^a which leads to the engine. This casing 1 has an internally screw threaded lower portion 3 into which is threaded a bearing element 4 in the form of the usual spider employed in devices 60 of this character and which permits the passage therethrough of air to the chamber formed within the casing 1.

A fuel supply nozzle 6 is slidably mounted 65 in the bearing element 4 and has its upper extremity reduced as at 7 while its lower extremity is threaded and engaged with a rotary plug valve casing 8 connected with a flexible fuel supply conduit 9 leading to a suitable source of supply (not shown). A 70 series of teeth 10 is formed on one side of the nozzle 6 and constitutes a rack with which a pinion 18 meshes and whereby the said nozzle may be reciprocated longitudinally to control the fuel and air supply to 75 the engine.

A cross rod 5 is arranged in the outlet conduit 1^a of the carbureter casing with the ends thereof suitably engaged with the opposed walls of said conduit and which forms 80 a support for a compensating valve 20 depending therefrom by a suitable stem 21'. This valve 20 is designed to coöperate with the reduced nozzle end 7 for a purpose presently to be described and it is equipped with 85 laterally extending fingers 21 which form guides for the valve.

A tapered air controlling valve 11 which is here shown substantially cone-shaped has beveled webs 12 formed on the lower sleeve 95 portion 11^a thereof at diametrically opposite points. This valve 11 is normally seated in the reduced portion 2 of the carbureter casing and has formed therein in alinement and communicating with the sleeve 11^a of the valve 100 a charge receiving and mixing chamber 13 the upper end of which is reduced and opened at the apex of the valve 11 to form a discharge nozzle as indicated by the numeral 14. Converging air ducts 15 communicate with an annular channel-like bore 105

15' of the charge mixing chamber 13 and open through the under side of the valve 11 outside the sleeve 11^a to permit ingress of air to the chamber 13. To normally maintain the valve 11 on its seat, a bearing collar 16 is mounted on the supply nozzle 6 being preferably threaded thereon and is designed to form an abutment for a coiled spring 17 arranged on the nozzle in advance 10 of said collar the other end of the spring bearing against the lower end of the valve sleeve 11^a. The tension of this coiled spring 17 operates to normally maintain the valve 11 on its seat and to return it to seated position 15 after it has been opened as will be hereinafter more fully described.

The sleeve 11^a has a longitudinally extending slot 12' to receive a pin 7' which projects laterally from the supply nozzle 6 20 to provide for independent movement of the nozzle for a predetermined distance.

From the above description it will be obvious that when the supply nozzle is moved downwardly within the mixing chamber 13 25 from the position shown in Fig. 2, to the position shown in Fig. 1 the pin 7' will be positioned at the lower end of slot 12' so that the continued downward movement of nozzle 6 will operate to unseat valve 11, thereby permitting a maximum quantity of 30 air to flow through the ducts 15 in said valve 11 and around the latter into the outlet or conduit 1^a; thereby forming a more perfect combustible mixture, the fuel being supplied through valve 24 and the nozzle 6. When the nozzle 6 is moved upward from 35 the position shown in Fig. 1 to the position shown in Fig. 2 it will close the air ducts 15 in valve 11 and said valve will be forced 40 to seated position by the spring 17 and thereby cut off the air supply to the conduit 1^a as shown in Fig. 2. This position of the valve and the nozzle is desirable for priming 45 of the engine for which purpose a rich mixture is necessary. It will thus be seen that by adjustment of nozzle 6 the air supply may be increased or decreased or entirely 50 cut off and such adjustment is under the control of the operator. The movement of this nozzle 6 also controls the opening and closing of the plug valve 24 as will be herein- 55 after more fully described.

The movement of the nozzle 6 to its downward limit provides for an additional supply 55 of air around the valve 11 to the intake conduit 1^a while the fuel passage is slightly restricted by movement of the valve 24. The restriction of the fuel passage tends to reduce 60 the flow of fuel, while the increased function of the engine at higher speeds tends to increase said flow. As a result a mixture of proper proportions, neither too rich in fuel contents nor too lean is provided. The nozzle is raised and lowered by means of a 65 pinion 18 engaging the rack 10, said pinion

being rotatably mounted in the bearing element 4 and carrying on its stub shaft an apertured operating arm 19 with which suitable actuating means (not shown) is engaged. This actuating means may extend 70 to the dash or some other point convenient to the operator. By rocking the arm 19 the 75 100 105 110 115 120 125 130 135 140 145 150 155 160 165 170 175 180 185 190 195 200 205 210 215 220 225 230 235 240 245 250 255 260 265 270 275 280 285 290 295 300 305 310 The compensating valve 20 shown in Figs. 1 to 5 comprises a double cone-shaped body the tapered extremities of which are provided one with an eye and the other with divergent guide arms 21 which operate with the nozzle 6. A depending arm 22 secured to the lower portion of element 4 is engaged by a bifurcated operating arm 23 secured at one end to the rotatable plug valve 24 so that the movement of the nozzle in either direction will turn valve 24 to decrease the supply of fuel fed therethrough. In Fig. 6 a slightly modified form of combined air valve and charge forming chamber 11 is provided. The upper extremity of the supply nozzle 6 of this form of the invention has a reduced portion 6' while, adjacent thereto the base of valve 11 has an enlarged opening 11' forming a chamber to receive a coiled spring 17' which operates in the manner similar to spring 17 in the other figures. By this arrangement a more compact form is afforded and the pin 7' and slotted sleeve of the structure shown in Figs. 1 and 3 is dispensed with. It is of course understood that these interengaging shoulders perform the same function as the pin and slot connection of the other figures. The term "fuel" as used in this description refers to hydrocarbon fuels such as are commonly used in internal combustion engines to combine with air to produce the combustible mixture or explosive charge and more especially to gasoline. The preferred embodiment of the invention is disclosed in the drawings and set forth in the specification, but it will be understood that any modifications within the scope of the claims may be made in the construction without departing from the principle of the invention or sacrificing any of its advantages. What I claim is:

1. In a carburetor, a casing, the lower portion of which serves as an air chamber, a fuel nozzle slidable within the casing, an air valve mounted on the fuel nozzle and having a mixing chamber communicating with air ducts formed therein, said fuel nozzle normally extending within the mixing chamber, a pin on the fuel nozzle for limiting its movement with respect to the air valve, said air valve coöperating with said nozzle for cutting off the air supply at 120 125 130 135 140 145 150 155 160 165 170 175 180 185 190 195 200 205 210 215 220 225 230 235 240 245 250 255 260 265 270 275 280 285 290 295 300 30

the termination of the upward movement of the fuel nozzle, and a compensating valve for controlling the flow of fuel from said fuel nozzle.

- 5 2. In a carbureter, a casing the lower portion of which serves as an air inlet chamber while the upper portion is reduced to form a seat and a mixture passage, an air valve disposed in the casing having a depending sleeve portion and formed with a mixing chamber in its top in communication with the sleeve portion and further provided with ducts for establishing communication between the mixing chamber and the
- 10 air chamber, a fuel supply nozzle vertically slidably through the bottom of the casing and slidably arranged in the sleeve portion of the air valve and communicating with the mixing chamber to coact therewith

in controlling the passage of air through the 20 valve, resilient means disposed about the nozzle and exerting its tension against the air valve to normally hold the air valve seated, a pin and slot connection between the nozzle and the air valve for permitting 25 of an upward independent sliding movement of the nozzle relative to the air valve yet insuring of the downward movement of the air valve when the nozzle is moved downwardly a predetermined extent, 30 a rod carried by the fuel supply nozzle and a pinion connected with means for manually operating the same for actuating the nozzle and consequently the air valve for regulating the quality of the mixture.

In testimony whereof, I affix my signature hereto.

VICTOR E. WASSERLEIN.
